INVENTOR

Victor J. Evans

ATTORNEY

John W. Wilson
WITNESS:

UNITED STATES PATENT OFFICE.

WILLIAM WILSON, OF NEW YORK, N. Y.

LIFE PRESERVER.

Application filed June 19, 1926. Serial No. 117,117.

This invention relates to improvements in life preservers.

The primary object of the invention resides in a life preserver which may be collapsed when not in use and carried in the pocket or bag of a tourist on a sea voyage for use in an emergency against drowning, and which may be made ready for use in quick time.

10 Another object of the invention is to provide a life preserver of the inflatable type and which may be inflated by a user under the surface of the water, without fear of water entering the buoyant elements.

15 Another object is to provide an emergency life preserver which when inflated for use is capable of supporting a relatively heavy body upon the surface of the water.

A further object is the provision of a life 20 preserver which is simple in construction, easy to assemble for use or collapse when not in use, and inexpensive of manufacture.

With these and other objects in view, the invention resides in certain novel construction and combination and arrangement of parts, the essential features of which are hereinafter fully described, are particularly pointed out in the appended claims, and are illustrated in the accompanying drawing, in 25 which:—

Figure 1 is a side elevation of my improved life preserver ready for use.

Figure 2 is an enlarged fragmentary sectional view therethrough.

35 Figure 3 is a detail sectional view on the line 3—3 of Fig. 2.

Figure 4 is a fragmentary vertical sectional view of the device when in a collapsed condition.

40 Figure 5 is a detail perspective view of the coacting locking means between the two closure sections.

Referring more particularly to the drawing, 10 designates my improved life preserver in its entirety and which includes a valve casing 11 having a longitudinal bore 12 therein, with which a transverse bore 13 communicates. Headed sleeves 14 thread into the opposed ends of the bore 12 for 45 clamping the open ends of a pair of balloons or bladders 15 and 16 to the casing for establishing communication between the bore 12 and the interior of the respective balloons. The balloons or bladders are of oval shape 50 to provide sufficient support for the body of a person when lying thereon. Also clamped

by the heads of the sleeves 14 are oval shaped nets 17 which respectively surround the balloons to limit inflation of the same and to retain them in proper shape. 60

Carried at the outer ends of the balloons are metallic shell members 18 and 19 which co-act as shown in Figure 4 of the drawing, to enclose the structure when in a deflated condition and not in use. Each shell member is supported by clamping the net 17 between the inner walls of the members and disks 19 by passing screws 20 through the respective members and into threaded recesses in the disks 19. 70

For simultaneously inflating the opposed balloons, I provide the casing 11 with an opening 21 in the top wall of the bore 13. Mounted within the bore 13 rearward of the opening 21 is a valve disk 22 having openings 23 therein while supported on the back of said disk is a flat flexible flap valve 24, adapted to normally close the openings 23 to prevent the escape of air from the balloons during and after inflation of the same. 80

For normally closing the opening 21 in the valve casing to prevent accidental entering of water into the balloon when the device is in use, I provide a pivoted closure member 25, normally held closed by a spring 26, and 85 which member is operable to an open position by a biting action on the part of a person upon a raised tail 27. From the description thus far, it will be seen that when the sections 18 and 19 are separated, the user inserts the mouth piece of the casing 12 in his or her mouth and bites upon the tail 27, to lift the closure member 25, to uncover the opening 21 and blows air into the casing through the said opening 21, openings 23 in 90 the valve disk, which causes the valve 24 to unseat, thus permitting an equal amount of air to pass through the opposite ends of the duct 12 into the balloons, until the same are fully inflated. In order to deflate the 100 balloons to permit of the collapsing of the device, the sleeves 14 are unscrewed from the valve casing by grasping the square heads of the same and turning them, it being understood that the thickness of the walls of the balloon cover the head. When fully unscrewed, the air in the balloons will immediately exhaust, after which the same may again be connected with the valve casing by threading the sleeves therewith. It might 105

be here stated that the sleeves 14 are fixedly connected with the balloons to prevent of 110

their separation and to provide an air proof joint between the same. After exhausting the air from the balloons, the two shell members may be brought together to enclose the 5 same.

For locking the shell sections in a closed position, I provide oppositely disposed slots 29 in the shell section 18 for the reception of the bills of a pair of pivoted clamping hook 10 members 30 respectively carried by pivoted levers 31 mounted within the walls of slots 32 provided in the section 18. For effecting the connection of the shell members, the levers 31 are swung outward, causing the 15 expansion of the hook members 30 to permit of their reception in the slots 29, after which the levers are pushed down to seat within the walls of the slots 32, causing the hook members to pull the two shell members into 20 tight engagement with each other. For unlocking and separating the shell members, the levers are again lifted to permit the hooks to be withdrawn from the slots 29.

From the foregoing description, it will be 25 seen that I have provided an emergency life preserver which is foldable into a compact case so as to permit the article to be carried in the pocket or bag of a person when taking sea trips for emergency purposes against 30 drowning. The device is so constructed as to be quickly assembled for use by an individual should an emergency arise, in a manner similar to that just described.

While I have described what I deem to 35 be the most desirable embodiment of my invention, it is obvious that many of the details may be varied without in any way departing from the spirit of my invention; and I therefore do not limit myself to the exact 40 details of construction herein set forth nor to anything less than the whole of my invention limited only by the appended claims.

What is claimed as new is:—

1. A life preserver comprising a pair of 45 inflatable members, nets surrounding said inflatable members for limiting inflation of the

same and for confining said members to the shape of said nets, means for allowing said inflatable members to be inflated simultaneously, means for retaining said inflatable 50 members in inflated condition and co-acting means carried by said inflatable members for housing the same in a collapsed condition.

2. A life preserver comprising a pair of oppositely disposed inflatable members, a 55 casing interposed between said inflatable members for supporting the latter, and co-acting shell members carried by the outer ends of said inflatable members for housing the inflatable members when in a collapsed 60 condition.

3. A life preserver comprising a pair of oppositely disposed inflatable members, a casing interposed between said inflatable members for supporting the latter, and co-acting shell members carried by the outer 65 ends of said inflatable members for housing the inflatable members when in a collapsed condition, and co-acting means between said shell members for locking the same in tight 70 engagement with each other.

4. A life preserver comprising a casing having a duct therein opening onto a mouthpiece provided thereon, a pair of oppositely disposed inflatable members, means for 75 removably supporting said inflatable members upon said casing in communication with said duct, a valve normally closing the entrance of said duct and operable to an open position by a biting action on the part of an 80 operator when the mouthpiece is inserted in the mouth for inflation of said inflatable members, and a check valve within said duct for preventing the escape of air from said 85 members after the same has been blown therein by the operator, and co-acting shell members carried by the ends of said inflatable members for housing said inflatable members when in a deflated condition.

In testimony whereof I have affixed my 90 signature.

WILLIAM WILSON.
